UNITED STATES PATENT OFFICE.

ALFRED GRAVES LAPE, OF HAMMONDSPORT, NEW YORK.

MAGAZINE INK-DISTRIBUTING DEVICE FOR PRINTING PRESSES.

Application filed December 1, 1923. Serial No. 677,933.

My invention relates to a magazine ink spreading knife particularly adapted for use on job printing presses.

The object of my invention, generally stated, is an ink applying and spreading knife or implement embodying an ink magazine incorporated therein as a part thereof and having means, including ink feeding and distributing passages leading from the magazine therethrough, for readily forcing the ink in the minute quantities desired through said passages and spreading the same over the disc or rolls of the printing press. A further object is a spreader of this character and of a construction enabling it to be readily lifted and manipulated by one hand, if desired, to supply the ink and spread it uniformly over the surface to be inked, and particularly a magazine knife of the character indicated which may be handled and manipulated with the greatest facility without the necessity of soiling the hands, thereby economizing the time of the operator heretofore consumed in using the old cumbersome and more or less unsatisfactory methods of dipping the old and ordinary spreading knife or wooden paddle into cans of ink and then smearing the ink over the surface, and also the time consumed in cleansing the hands which has heretofore often been necessary after the smearing operations before the job can be handled. A further object of my invention is to conserve the printing ink, and this I accomplish by the economical manner in which, by the use of my invention, I am enabled to apply and spread the ink and also by avoiding the substantial loss by drying up in the air which has heretofore been experienced with the open can dipping devices and methods. A still further object of my invention is a device of the character indicated which is of simple character and which may be economically manufactured and easily assembled for use.

For a better understanding of my invention, including the above indicated novel features and others which will hereinafter appear, reference may be had to the accompanying drawings forming a part of this application, wherein:

Fig. 1 is a plan view of my novel magazine ink knife,

Fig. 2 is a vertical section therethrough,
Fig. 3 is a bottom view of the knife,
Fig. 4 is a perspective view indicating the method of use, and

Fig. 5 is a section of a slightly modified form of my novel device.

Referring to the drawings, my novel ink spreading knife comprises a relatively extended spreading surface or member 1 and a magazine or reservoir 2, the spreading member 1 in the embodiment illustrated being of circular plate disc-like form and the magazine being of cylindrical form of substantially smaller diameter than that of the spreading disc. The spreading member 1 forms the bottom or the closure for one end of the cylindrical wall 2 of the magazine and, as illustrated in the embodiment of Figs. 1-3, the member 1 is screw-threadedly attached and sealed to the cylindrical part 2 by means of an internally threaded sleeve 3 formed integrally with the member 1 and cooperating with external screw-threads on the lower end of the cylindrical part 2. The cylindrical or tubular part 2 is screw-threaded internally, preferably substantially throughout its length, for the reception of an externally threaded cylindrical member 4 having a closed bottom 5, and in the embodiment of Figs. 1-3 this bottom 5 is integral with the cylindrical part 4 for convenience in manufacture. The member 4 serves both as a closure for the upper end of the cylindrical part 2 and as a plunger for applying pressure upon the ink contained therein. Within the upper end of the inner part 4 of the device, there is disposed an externally threaded plug 6 which may be inserted through the upper open end and screwed downwardly to the position desired. In the upper end 7 of this plug 6 there are provided radial screw-threaded openings, in the particular embodiment illustrated, four in all, for the reception of the screw-threaded manipulating fingers 8, the latter passing out through openings formed near the upper end of the cylindrical inner member 4. The member 1 is provided with a number of small passages 9 (four in the embodiment shown) leading from the interior of the magazine 2 to the bottom surface of the spreading member, these passages serving as feeding and ink-distributing apertures

when the magazine knife is applied to the surface to be inked and the feeding or inner member 4 is gradually screwed downwardly by the manipulation of the fingers 8 to apply pressure upon the ink. The device as a whole is provided with a handle 10 which may be secured thereto in any suitable manner, as for example by brazing to the exterior of the member 2 with this handle projecting out at right angles thereto and permitting a ready grip thereof by the hand, with the thumb free to manipulate the fingers 8 in the act of applying and spreading the ink on the disc or roll of the printing press. The relative dimensions of the parts may be varied within limits to suit the requirements of the particular case, but those illustrated are preferred wherein the intermediate cylindrical wall 2 is of greater depth than diameter or width and the spreading and closing member 1 for the cylinder 2 is of extended surface and of substantially larger area than the projection of the cylinder 2. In use the ink is contained within the cylindrical or tubular containing wall 2 of the magazine, and the bottom 1 and the inner and upper member 4 form tight closures therefor, thereby securing substantially air tight or leakless seals to prevent the leakage of the ink therefrom and the entry of air thereto, the drying up of the ink due to access to the air being substantially reduced and the ink thereby conserved. Moreover, the device may be manipulated and adjusted during the actual application and spreading of the ink to feed and supply the exact quantities desired without any necessary waste of ink and without the necessity for soiling the hands. When the ink becomes depleted, the device may be refilled either at the top or the bottom, namely by removing either the closing, distributing and spreading member 1 or by removing the inner member 4, and when not in use the device may be suspended or laid in any position, as the ink will not ordinarily leak through the apertures 9 unless under pressure.

In Fig. 5 I have shown a slight modification wherein the spreading and distributing member 1' is brazed to the bottom of the magazine part 2' and the bottom 5' for the inner member 4' is in the form of a plug or disc, fitting tightly within the lower end thereof and anchored in place by a pin 11 passing radially therethrough and diametrically through the lower end of the inner member 4'. The upper end of the inner member 4' is provided with a single finger or handle 12 which passes through registering openings in the opposite sides of the upper end of the cylindrical member 4' and forms a pair of oppositely disposed manipulating handles for screwing the inner member 4' downwardly and feeding the ink in

the quantities desired through the feeding passages 9'. The device of this modification and the modification illustrated in Figs. 1-3 may be of any material desired, but preferably of readily workable steel.

In accordance with the requirements of the patent statutes, I have set forth my invention in the specific manner required thereby, but it is understood that the novel features thereof are capable of assuming other forms than the specific embodiments illustrated, and that the claims annexed hereto are intended to cover all such modified forms coming within the scope and spirit of my invention.

I claim:

1. An ink distributing device for printing presses comprising an ink magazine, a feeding plate forming a closure for one end of said magazine and having minute feeding and distributing passages leading from the ink magazine chamber therethrough to the surface of the closing plate, an adjustable closing and feeding member secured within the upper end of the magazine for both forming a closure therefor and applying pressure to the ink contained in the magazine to force it out through the aforesaid passages, an operating member for the adjustable closing member and a manipulating and lifting handle secured to the exterior of said magazine, said operating and manipulating members being arranged and adapted to be engaged simultaneously by the hand.

2. An ink spreading knife for printing presses comprising a tubular ink magazine container, a feeding and spreading plate forming a closure for one end of the magazine and having minute feeding and distributing passages leading from the interior of the chamber through said spreading member to the spreading surface thereof, an elongated adjustable closure for the other end of said magazine container having an operating member at its upper end for adjusting the position thereof within the ink magazine and applying pressure to the ink contained therein and a manipulating and lifting handle secured to the exterior of said magazine part in a position to be readily gripped by the forefingers, leaving the thumb free to actuate the aforesaid operating member.

3. An ink spreading knife for printing presses comprising an internally threaded tubular ink magazine, a closure for one end thereof comprising an ink spreading plate and the latter having a screw-threaded sleeve formed integrally therewith and adapted to be screw-threadedly attached to form a tight closure for one end of said magazine, and means for forcing ink out of said magazine under pressure, including a number of minute feeding and distributing passages leading from the magazine through said spreading plate to the spreading surface thereof,

- and an externally screw-threaded closing member cooperating with internal threads formed on the inner surface of said ink magazine for forming both a closure for one end 5 thereof and applying pressure to the ink for forcing the ink in minute quantities through the aforesaid passages leading from the reservoir to the surface of the spreading member.
- 10 4. A magazine ink spreading knife for printing presses comprising an internally threaded cylindrical ink container, a closing and ink spreading plate having a screw-threaded sleeve detachably engaging one end 15 of said cylindrical container, said spreading plate being of extended surface compared to the diameter of the cylinder, an externally screw-threaded cylindrical member having one end closed and adapted to be screwed 20 home into the open end of said cylindrical container to form both a closure therefor and a pressure applying medium for the ink contained therein, an operating handle se-

cured to the upper end of said externally threaded closure and pressure applying 25 member, and said spreading and closing member of extended surface having a plurality of feeding and distributing passages leading from the interior of the ink magazine to the spreading surface thereof. 30

5. A device of the character set forth in claim 4, comprising a holding and lifting handle secured to said device in a manner to be readily gripped by the forefingers, with the thumb free to engage the operating handle 35 of the pressure applying and closing member.

6. A device of the character set forth in claim 4 in which the operating handle is screw-threadedly attached to an externally 40 screw-threaded plug screwed down into the upper end of the externally screw-threaded cylindrical member.

In testimony whereof, I have signed my name to this specification.

ALFRED GRAVES LAPE.
